UNITED STATES PATENT OFFICE.

WILLIAM D. RUNDLETT, OF NORTH ANDOVER, MASSACHUSETTS.

SEWING-MACHINE.

SPECIFICATION forming part of Letters Patent No. 570,962, dated November 10, 1896.

Application filed August 29, 1895. Serial No. 560,872. (No model.)

To all whom it may concern:

Be it known that I, WILLIAM D. RUNDLETT, formerly of the city and county of Providence, in the State of Rhode Island, but now residing at North Andover, in the county of Essex and State of Massachusetts, have invented certain new and useful Improvements in Wax-Thread Sewing-Machines; and I do hereby declare the following specification, taken in connection with the accompanying drawings, forming a part of the same, to be a full, clear, and exact description thereof.

The present application is intended to take the place, and is a continuation, of application Serial No. 437,877, filed June 24, 1892, and the renewal thereof, Serial No. 537,304, filed February 4, 1895, which latter application is to be abandoned.

This invention relates to wax-thread sewing-machines such as are employed for sewing leather. As is well known, it is necessary in machines of this character in which a hook-needle is employed to form a loop of thread upon that side of the work which is opposite to the side from which the needle operates, which said loop of thread is subsequently engaged by the hook of the needle and pulled into the work. The purpose of forming this loop of thread is to prevent rendering of the 30 thread through the hook of the needle while in the work. It is desirable in the formation of this loop that there should be as little rendering as possible of the thread through or over any of the loop-forming devices.

35 In another application, filed June 24, 1892, Serial No. 437,876, I have shown and described a sewing-machine for uniting the soles of boots and shoes to their uppers which embodies a novel organization and combination of loop-forming devices, whereby the injurious effects of the thread rendering through or over the loop-forming devices are materially reduced. In the arrangement there shown, however, there is a rendering of the thread not 40 only through the thread-eye, but also over the thread-arm.

The object of the present invention is to still further reduce the injurious effects of the thread rendering through or over the loop-forming devices during the formation of the 45 loop; and to that end the invention consists

in the combinations and arrangements of parts hereinafter described, whereby all rendering of thread over the thread-arm during the formation of the loop is entirely avoided. 55

For the purpose of illustrating the present invention I have shown the same in the accompanying drawings as applied to a sewing-machine for uniting the soles of boots and shoes to their uppers. It will be understood, 60 however, that the invention is applicable to any form of machine in which it is desirable to form a loop to be subsequently drawn into the work.

As the present invention relates only to the 65 loop-forming devices I have shown in the accompanying drawings only so much of a sole-sewing machine, with the present invention applied thereto, as will be necessary to illustrate the construction and operation of such 70 loop-forming devices.

Referring to the drawings, Figure 1 is an end elevation of a portion of a sole-sewing machine with my invention applied thereto, a part of the frame being broken away to show the construction and arrangement of the loop-forming devices. Fig. 2 is a section on the line *y* *y* of Fig. 1; and Figs. 3 to 9, inclusive, 75 are diagrammatic views showing the different positions of the loop-forming devices in 80 forming the loop of thread.

In the machine shown in the drawings the operating parts are embodied in a head which is adapted to be mounted upon and secured to a suitable column or support *A*. This head 85 consists of a suitable framework *B*. The machine is provided with a driving-shaft *C*, journaled in suitable supports. To this driving-shaft are secured the necessary cam-disks for actuating the different parts of the machine. 90 As the present invention does not relate in any way to the construction or arrangement of these cam-disks, but only to the construction and arrangement of parts or devices to be operated thereby, it has not been deemed necessary to show all of said cam-disks in the drawings, and only one of the same, to wit, the cam-disk *D*, is shown. 95

The machine shown in the drawings is to be provided with a shuttle mounted in the 100 shuttle-race *1*, which is secured to the framework *B*. Secured to this shuttle-race *1* is the

fixed work-support 2, against which the work 3 is to be clamped by a presser-foot. (Not shown in the drawings.)

4 represents a curved hook-needle which 5 may be operated in any well-known manner.

The loop-forming devices consist of a thread-eye 5 and a thread-arm 6, to the latter of which certain novel and peculiar movements are given to draw out the loop of thread. The 10 thread-eye 5 is arranged between the work and the take-up 7, and through said thread-eye the thread passes on its way from the take-up to the work, as shown in the drawings. This thread-eye is given not only an 15 oscillating movement for the purpose of laying the thread into the barb of the needle, but is also given a vertical movement for the purpose hereinafter described. The thread-eye 5 is secured to the end of the bar 8, which 20 is capable of sliding vertically in suitable bearings attached to the frame of the machine. For giving to the thread-eye the necessary oscillating movement the bar 8 is provided with a crank 9, the hub of which crank 25 surrounds the bar 8 and is provided with a feather which enters a longitudinal groove in the bar 8, whereby said bar may be turned upon its axis by said crank 9, but will be free to slide vertically in the hub thereof. To the 30 crank 9 is pivoted a connecting-rod 10, the opposite end of which connecting-rod is pivoted to the end of the lever 11, which said lever is pivoted at 12 to a bracket secured to the frame. Said lever 11 is provided with a 35 roller 13, which rides in a suitable cam-groove in one of the cam-disks secured to the driving-shaft C. By the mechanism above described the thread-eye 5 will be given the proper oscillating movements required.

40 Surrounding the upper end of the bar 8 is a sleeve 14, arranged between a shoulder on said bar and a nut upon the end of the bar, as shown in Fig. 2. The sleeve 14 is connected to the free end of the lever 15 by means 45 of the connecting-link 16. The lever 15 is pivoted to the frame at 17 and is provided at its other end with a roller 18, adapted to ride in a suitable cam-groove in one of the cam-disks secured to the driving-shaft C. 50 By the mechanism above described the thread-eye is given an intermittent vertical movement, as hereinafter described.

The thread-arm 6 is pivoted at 19 to the 55 end of the lever 20, which said lever is pivoted to the frame at 21, as shown in Fig. 1. To the thread-arm 6 novel and peculiar movements are given by mechanism which will now be described. To the lever 20 is pivoted one end of a connecting-link 22, the other end of 60 which link is connected to one end of a bell-crank lever 23, pivoted to the framework at 24. The other end of the bell-crank lever 23 carries a roll 25, which is adapted to ride in a suitable cam-groove in one of the cam-disks 65 secured to the driving-shaft C. The thread-arm 6 is provided with a tail or extension which is pivoted at 26 to one end of a con-

necting-link 27, the other end of which link is pivoted to the end of a bell-crank lever 28, which is pivoted to the frame at 29. The 70 other end of the bell-crank lever 28 is provided with a roll 30, which is adapted to ride in a cam-groove in one of the cam-disks secured to the driving-shaft C.

The operation of the loop-forming devices 75 above described in forming a loop of thread is as follows, reference being had to the diagrammatic views, Figs. 3 to 9, inclusive: The parts being in the position shown in Figs. 1 and 4, being the position of the parts at the 80 completion of the last preceding stitch, the several cam-grooves in the cam-disks secured to the driving-shaft are so constructed and timed that the thread-eye will stand still in the elevated position shown in Figs. 3 and 4, 85 while the thread-arm is moved from left to right, Fig. 4, under the action of the lever 20, link 22, bell-crank lever 23, and its actuating cam-groove. At this time there is no movement given to the bell-crank lever 28, and 90 consequently the tail of the thread-arm will be held by the connecting-link 27, thereby causing the thread-arm to turn upon its pivot 19, and so that as the thread-arm is drawn back by the link 22 the pivot 26 will be caused to 95 describe the arc of a circle and will travel from *a* to *b*, Fig. 4. The result of this compound movement given to the thread-arm 6 in drawing back the loop will be to cause the hook of said thread-arm to describe the arc 100 of a circle and to travel from *a'* to *b'*, Fig. 4, and it will be seen that the arc which the hook of the thread-arm so travels is described not from the pivot 21, but instead from the point of junction of the thread with the work—viz., 105 from the point *x* as a center. By this movement of the thread-arm the loop of thread will be drawn out, as shown in Fig. 6.

When the thread-arm has reached the position shown in Fig. 6, it is caused to remain 110 at rest in that position, while the thread-eye 5 is, by means of the connecting-link 16, the lever 15, and its actuating cam-groove, caused to descend from the position shown in full lines to the position indicated in dotted lines 115 in Fig. 6, thereby bringing said thread-eye into the proper vertical position for laying the thread into the barb of the needle. At the same time, and while the thread-eye is moving downward, it is caused, by means of the crank 9, connecting-rod 10, lever 11, and its actuating cam-groove, to be oscillated or turned about the axis of the bar 8. As the 120 result of these two movements the thread-eye is moved from the position shown in full 125 lines to the position indicated in dotted lines, Fig. 5, thus bringing the thread into a position at the right of the needle and so that it may be laid into the barb of the needle. During this time the needle has been moved up 130 through the work, and by the time the thread-eye has reached its lowermost position the needle has reached its highest position, as shown in Fig. 8. The thread-eye is then os-

cillated in the opposite direction and so as to lay the thread into the barb of the needle, as shown in Figs. 7 and 8. The needle then begins to descend, and at the same time the thread-arm is moved forward to enable the loop which has been formed to be drawn down through the work by the needle, the thread-arm thus following up and delivering said loop as it is being drawn down until the loop frees itself from the hook of the thread-arm, as shown in Fig. 9. Simultaneously with the commencement of the forward movement of the thread-arm to deliver the loop to the needle the lever 28 is operated by its cam-groove 15 to gradually lift the link 27 and the tail of the thread-arm 6, and so that as the thread-arm is moved forward by the link 22 the pivot 26 will be moved through the path *b c*, Fig. 4, and into the position shown in full 20 lines in Fig. 9. By the combined action of the levers 23 and 28 and their connecting-links the hook of the thread-arm during the forward movement of said arm is caused to travel in the arc of a circle from *b'* to *c'*, Fig. 25 4, and into the position shown in full lines in Fig. 9. Just before the forward movement of the thread-arm in delivering the loop to the needle is completed the thread-eye is, by the proper mechanism, raised to the position shown in Fig. 9. After the loop has 30 been drawn off from the hook of the thread-arm, and after the thread-eye has been raised to its elevated position, the thread-arm is returned to its original position to reengage the 35 thread for the formation of the next loop. This last movement of the thread-arm is effected solely by the lever 28 and the link 27, the lever 20 at this time remaining stationary, whereby the proper movement of the lever 28 and link 27 will serve to swing the thread-arm on the pivot 19 and cause the hook of the thread-arm to travel in the arc 40 of a circle from *c'* to *a'*, Fig. 4, or from the position shown in full lines to the position indicated in dotted lines in Fig. 9.

As will be seen upon reference to Fig. 4, the hook of the thread-arm in traveling from the point *c'* to the point *a'* is moved from the rear to the front of the thread. In order to prevent this movement of the hook of the thread-arm from interfering with the thread, the thread-eye, when oscillated to lay the thread into the barb of the needle, as above described, is not returned completely to the position from which its oscillating movement began, but instead is moved only a portion of the entire distance, and so that when the thread-eye is raised to its elevated position it will stand in the position indicated in dotted lines in Fig. 3, in which position, as shown in dotted lines in said figure, the thread will be held to one side of the path of movement of the hook of the thread-arm, and so that the latter may pass without interference. After the thread-arm has reached the position shown in Fig. 4 the thread-eye is oscillated the remainder of the required distance to re-

turn said thread-eye to its original position, that is, is moved from the position shown in dotted lines to the position shown in full lines, Fig. 3, thereby bringing the thread into the path of movement of the hook of the thread-arm, and so that it will be engaged thereby upon the next rearward movement of said thread-arm. After the loop has been formed by the loop-forming devices, and the thread is laid into the barb of the needle by the oscillation of the thread-eye, the needle begins to descend and draws the thread composing the loop so formed down into and through the work in the usual manner, as shown in Fig. 9, the needle thus drawing out a loop upon the other side of the work to be engaged by the shuttle. The thread to form the loop so drawn through the work by the needle is furnished partly by the loop formed by the loop-forming devices above described and partly by thread which is delivered up by the take-up at this time, thereby avoiding any rendering of the thread through the hook of the needle in its passage through the work.

As will be seen, the loop of thread is substantially all drawn out by the thread-arm. During this drawing out of the loop by the thread-arm there will necessarily be a rendering of the thread through the thread-eye, but by reason of the vertical movement given to said thread-eye and the fact that said thread-eye is caused to occupy an elevated position during the operation of the thread-arm in drawing out the loop the angle at which the thread is drawn from the thread-eye is greatly increased, whereby the tendency to abrade the thread as it renders through the thread-eye is materially reduced. The subsequent downward movement given to the thread-eye is solely for the purpose of returning it to the proper vertical position to lay the thread into the barb of the needle, and such downward movement does not cause any substantial addition to the loop drawn out by the thread-arm, and with the result that there is practically no rendering of thread through the thread-eye during said downward movement.

As already pointed out, the hook of the thread-arm in moving backward to draw out the loop is caused by the mechanism above described to move in the arc of a circle about the point *x* at the junction of the thread and the work as a center. The thread being anchored or held at the point *x* it follows that the distance between said point *x* and the hook of the thread-arm will not be changed during the backward movement of the thread-arm in drawing out the loop, and consequently there will be no rendering of the thread over the thread-arm during the formation of said loop.

By the peculiar method of operating the thread-arm above described all rendering of thread over the thread-arm in the formation of the loop is avoided, and by raising the thread-eye to an elevated position the inju-

rious effects of the thread rendering through the thread-eye during the operation of the thread-arm are materially reduced, and by the combination of the thread-eye and thread-arm, operated as described, the rendering of thread during the formation of the loop and the injurious effects thereof are reduced to a minimum.

What I claim as my invention, and desire to secure by Letters Patent, is--

1. In a sewing-machine the combination with a hook-needle and a thread-eye, of a thread-arm, and mechanism for moving the hook of said thread-arm in the arc of a circle described from the point of junction between the thread and the work as a center, substantially as described.

2. In a sewing-machine the combination with a hook-needle and thread-eye, of a thread-arm, and mechanism for moving the hook of said thread-arm in a triangular path, substantially as described.

3. In a sewing-machine the combination with a hook-needle and a thread-eye, of a thread-arm, two levers for operating said arm, one of said levers being pivoted to said arm intermediate of its ends, and the other

of said levers being connected to one end of said thread-arm, and means for operating said levers, whereby a compound movement 30 will be given to the hook of said thread-arm, substantially as described.

4. In a sewing-machine the combination of a hook-needle and a thread-arm, mechanism for moving the hook of said thread-arm in 35 the arc of a circle described from the point of junction between the thread and the work as a center, a thread-eye, and means for giving to said thread-eye a movement substantially in the line of the standing thread as and for the purpose specified.

5. In a sewing-machine the combination with a hook-needle and a thread-arm, of mechanism for moving the hook of said thread-arm in a triangular path, a thread-eye, and mechanism for giving to said thread-eye a movement substantially in the line of the standing thread as and for the purpose specified. 45

WILLIAM D. RUNDLETT.

Witnesses:

KATE C. FRYE,
PAUL M. CHASE.

It is hereby certified that Letters Patent No. 570,962, granted November 10, 1896, upon the application of William D. Rundlett, of North Andover, Massachusetts, for an improvement in "Sewing-Machines," were erroneously issued to said Rundlett as sole owner of the invention; whereas said Letters Patent should have been issued to *William H. Haskell, of Pawtucket, Rhode Island*, said Haskell being assignee of the entire interest in said invention, as shown by the assignment of record in this Office; and that the said Letters Patent should be read with this correction therein that the same may conform to the record of the case in the Patent Office.

Signed, countersigned, and sealed this 29th day of December, A. D., 1896.

[SEAL.]

JNO. M. REYNOLDS,
Assistant Secretary of the Interior.

Countersigned:

JOHN S. SEYMOUR,
Commissioner of Patents.
